UNITED STATES PATENT OFFICE.

JOHN M. RICHARDSON, OF MILWAUKEE, WISCONSIN.

DAVENPORT.

Application filed February 27, 1923. Serial No. 621,562.

To all whom it may concern:

Be it known that I, JOHN M. RICHARDSON, a citizen of the United States, and resident of Milwaukee, in the county of Milwaukee and State of Wisconsin, have invented certain new and useful Improvements in Davenports; and I do hereby declare that the following is a full, clear, and exact description thereof.

10 This invention relates to improvements in foldable couch beds of the davenport or day-bed type, in which a section of bed frame is normally housed beneath the seat, which seat serves as an extension to the bed frame section when swung to its inverted position before the couch.

15 The primary object of the present invention resides in the provision, of a simple and economical structure of the above character, that is capable of use in connection with a hair spring mattress, heretofore considered impractical for the reason that a mattress of this type cannot be folded, and consequently its proper housing beneath the seat has presented serious difficulties.

20 Incidental to the foregoing, a further object resides in the provision of means for automatically shifting that portion of the mattress supported on the section of bed frame which is normally housed beneath the seat.

25 A more specific object is to provide a simple structure of counterbalance adapted to serve as a cushion, for the folding parts at the end of their folding movement, and to initially assist in the extending operation.

30 A still further object is to provide a convertible couch structure which is detachably connected to the couch frame and may, therefore, be readily detached for shipping, repairing, and so on.

35 With the foregoing and other objects in view, the present invention consists of what is herein shown and described and more particularly pointed out and defined by the appended claims, it being understood that various changes and modifications in the structural details are contemplated as within the invention.

40 In the drawings:—

45 Figure 1 is a plan view of a davenport constructed within the plans of the present invention, parts of the davenport frame being in section to more clearly illustrate the structural features.

50 Figure 2 is a transverse sectional view

taken on the line 2—2 of Figure 1, and illustrates the various parts in their bed-forming position.

55 Figure 3 is a similar view illustrating the parts in one of their intermediate positions.

60 Figure 4 is a similar view illustrating another intermediate position.

65 Figure 5 is a similar view illustrating the parts in their couch-forming position.

70 Figure 6 is a detail sectional view taken on the line 6—6 of Figure 5.

75 Figure 7 is a detail sectional view taken on the line 7—7 of Figure 1.

80 Figure 8 is a detail sectional view taken on the line 8—8 of Figure 1.

85 Referring now more particularly to the accompanying drawings, wherein the present invention is illustrated in connection with a bed davenport, the numeral 1 designates a pair of end standards connected at the rear by a stationary upholstered back 2, and at their front by a face board 3, to form a davenport frame. Pivoted between the end standards 1, adjacent their front ends, is a seat section 4, which, when folded to couch-forming position, as illustrated in Figure 5, supports an upholstered cushion A, preferably of the hair spring type, the same being indicated in dotted lines. Secured to the sides of the seat section 4, adjacent its pivoted end, are a pair of brackets 5, to which are pivoted at 6 a pair of ears 7, that in turn carry an inner bed-frame section 8, preferably constructed of angle iron, to form a skeleton frame. Secured to the ears 7 are a pair of plates 9, adapted to abut the brackets 5, thus serving as a stop to maintain the seat section 4 and bed frame 8 in alignment, when the davenport is being converted into its bed-forming position, as illustrated in Figures 2 and 3.

90 From the foregoing description, it will be seen that, as the seat section 4 is swung outwardly from its couch-forming position, illustrated in Figure 5, the forward end of the inner bed frame section 8, which is pivotally connected to the seat section 4, will be lifted, as illustrated in Figure 4, to a point where the brackets 5 are engaged by the plates 9, after which the inner end of the bed section 8 will be raised as the seat section is swung downwardly to its bed-forming position, as shown in Figure 2.

95 In order to support the inner end of the bed section 8, and relieve strain from its

hinged connection with the seat section, I provide a pair of spring control latches 10, which are pivotally connected to the brackets 11, secured to the end standards 1. The 5 latches 10 are held in their normal position against the stops 12 projecting from the brackets 11, by means of the springs 13. Co-operating with the latches 10 are a pair of brackets 14, secured to the sides of the bed 10 frame 8, adjacent its inner end, the brackets 14 being provided with lateral extensions 14', which extensions, upon upward movement of the bed frame 8, will wipe past the latches 10, and when the bed frame section 15 8 has been raised to its bed-forming position, illustrated in Figure 2, the latches 10, by means of the springs 12, are caused to swing under the extensions 14' and support the same.

20 It is further obvious that, upon initial movement of the seat member 4 from its bed-forming position, the hinge joint between it and the bed frame 8 will break and the inner end of the bed section will be 25 forced rearwardly until the lateral extensions 14' drop off of the latches 10, after which, further swinging movement of the seat member 4 will cause the inner end of the bed frame section to move downwardly 30 until the lateral projections 14' engage the supports 15, secured to the end standards adjacent their lower portion, as illustrated in Figure 3. Further movement of the seat member 4 to the position illustrated in Figure 4 will cause the joint between the seat and bed frame to break, and as this movement takes place, it will be seen that the inner end of the bed frame section 8 is 35 40 45 50 55 60 65 70 75 80 85 90 95 100 105 110 115 120 125 130 135 140 145 150 155 160 165 170 175 180 185 190 195 200 205 210 215 220 225 230 235 240 245 rear edge. In the folded position of the seat member, illustrated in Figure 5, the levers 27 engage the angular brackets 28, carried by the angle irons 20 of the extension 18, 5 and inasmuch as the springs 27', which actuate the levers 27, are expanded in this position of the levers, it is obvious that a slight pull on the seat member 4 will cause it to raise with little effort, being assisted by the levers 27. It will be further seen that, upon completion of the folding movement of the seat member, to its davenport position, the angular brackets 28 will be engaged by the levers 27, which cushion the holding movement and insure the retraction of the extension 18, thus preventing the same from becoming accidentally extended. When in closed position, the seat member 4 is supported by means of the brackets 29, which 15 engage extensions 30, formed integrally with the plates 11.

To facilitate removal of the foldable parts from the davenport frame, I provide a detachable pivotal connection between these 25 parts, which comprises a pair of plates 31, connected to the end standards and provided with notches 32, which are adapted to receive the headed pivots 33, carried by the brackets 34, that are secured to the sides of 30 the seat member 4. Thus it is obvious that, by loosening the front connection between the end standards 1, the foldable mechanism, including the seat and bed frame sections, can be readily removed from the main frame.

35 Attention is further directed to the adaptability of the present invention to a couch bed of the day-bed type, in which instance, due to the greater width of a day-bed, the seat and bed frame sections can be increased 40 in width to accommodate the section of mattress, without necessitating the extension 18 and the shiftable mattress support 16,—otherwise the structure remains the same. It will also be noted that very little effort is 45 required to convert the structure from one position to another, due to the fact that the seat and frame section serve as a counterbalance for one another, with the exception of the initial opening movement and the end of 50 the closing movement, at which time the load is relieved by the counterbalance levers 27.

I claim:

1. In a structure of the character set forth, the combination of a main frame including end standards connected by stationary front and rear members, a seat pivotally connected to the main frame and adapted to swing outwardly to an inverted position, a bed frame section pivotally carried by the seat and normally housed beneath the same, an auxiliary frame slidably carried by the bed frame section, and means for reciprocating the auxiliary frame upon movement of the seat.

65 2. In a structure of the character set forth,

the combination of a main frame including end standards connected by stationary front and rear members, a seat pivotally connected to the main frame and adapted to swing outwardly to an inverted position, a bed frame section pivotally carried by the seat and normally housed beneath the same, an auxiliary frame slidably carried by the bed frame section, and means for retracting the auxiliary frame upon outward movement of the seat 70 and extending the same upon folding movement of the seat.

3. In a structure of the character set forth, the combination of a main frame including end standards connected by stationary front 80 and rear members, a seat pivotally connected to the main frame and adapted to swing outwardly to an inverted position, a bed frame section pivotally carried by the seat and normally housed beneath the same, an auxiliary 85 frame slidably carried by the bed frame section, and a link connection between the seat and auxiliary frame for reciprocating the latter, upon movement of the seat.

4. In a structure of the character set 90 forth, the combination of a main frame including end standards connected by stationary front and rear members, a seat pivotally connected to the main frame and adapted to swing outwardly to an inverted position, a bed frame section pivotally carried by the seat and normally housed beneath the same, an auxiliary frame slidably carried by the bed frame section, and a link connection between the seat and auxiliary frame for re- 95 tracting the latter upon outward movement of the seat and extending the same upon folding movement of the seat.

5. In a structure of the character set 100 forth, the combination of a main frame including end standards connected by stationary front and rear members, a seat pivotally connected to the main frame and adapted to swing outwardly to an inverted position in front of the same, a bed section pivotally 105 carried by the seat and normally housed beneath the same, said section being flush with the seat when the latter is in its inverted position, collapsible supports carried by the seat to support the latter when in its bed forming position, a bed frame section pivotally carried by the seat and normally housed beneath the same, an auxiliary frame 110 slidably carried by the bed frame section, means for reciprocating the auxiliary frame 115 upon movement of the seat, and an extension for said seat.

6. In a structure of the character set 120 forth, the combination of a main frame including end standards connected by stationary front and rear members, a seat pivotally connected to the main frame and adapted to swing outwardly to an inverted position in front of the same, a bed section pivotally 125 carried by the seat and normally housed be-

neath the same, an auxiliary frame slidably carried by the bed frame section, legs pivoted to the outer end of the seat, and a connection between the legs, bed frame section and auxiliary frame whereby the legs and auxiliary frame are actuated upon movement of the seat.

7. In a structure of the character set forth, the combination of a main frame including end standards connected by stationary front and rear members, a seat pivotally connected to the main frame and adapted to swing outwardly to an inverted position in front of the same, a bed section pivotally carried by the seat and normally housed beneath the same, an auxiliary frame slidably carried by the bed frame section, legs pivoted to the outer end of the seat, a link connecting said legs with the bed frame section whereby the latter are swung to their supporting position as the seat is swung outwardly, and collapsed as the seat is folded to its couch position, and a link connecting the first mentioned link and auxiliary bed frame section, whereby the latter is reciprocated upon movement of the seat.

8. In a structure of the character set forth, the combination of a main frame including end standards connected by station-

ary front and rear members, a seat pivotally connected to the main frame and adapted to swing outwardly to an inverted position in front of the same, a bed section pivotally carried by the seat and normally housed beneath the same, an auxiliary frame slidably carried by the bed frame section, an extension for said seat, legs pivoted to the outer end of the seat, links connecting said legs with the bed section whereby the latter are swung to their supporting position as the seat is swung outwardly and collapsed as the seat is folded to its couch position, links connecting the first mentioned links and auxiliary bed frame whereby the latter is reciprocated upon movement of the seat, a latch for supporting the inner ends of the bed frame section when the latter is in its bed forming position, and a spring controlled lever engageable by the extension for said seat whereby the closing movement of the seat is cushioned and the extension held in its retracted position with relation to the seat, said lever also serving to assist in the initial lifting operation of the seat. 55

In testimony that I claim the foregoing I have hereunto set my hand at Milwaukee, in the county of Milwaukee and State of Wisconsin.

JOHN M. RICHARDSON.
